BY *H. S. Fisher*

ATTY.

UNITED STATES PATENT OFFICE.

ALBERT T. FISCHER, OF CLEVELAND, OHIO.

DESIGN FOR A CLOCK-CASE.

No. 37,853.

Specification for Design.

Patented Feb. 27, 1906.

Application filed January 8, 1906. Serial No. 295 191. Term of patent 7 years.

To all whom it may concern:

Be it known that I, ALBERT T. FISCHER, a citizen of the United States, residing at Cleveland, in the county of Cuyahoga and State of Ohio, have invented a new and original Design of a Clock-Case, reference being had to the accompanying drawing, forming part thereof, and in which the figure is a perspective view showing the design of the clock.

I claim—

The ornamental design for a clock-case, as shown.

ALBERT T. FISCHER.

Witnesses:

R. B. MOSER,
C. A. SELL.
